UNITED STATES PATENT OFFICE

CRAWFORD C. LOOMIS, OF ILION, NEW YORK, ASSIGNOR TO REMINGTON ARMS COMPANY, INC., A CORPORATION OF DELAWARE

FIREARM

Application filed September 11, 1930. Serial No. 481,275.

This invention relates to firearms, and particularly to firearms of the magazine type, and has for its object the provision of devices for the purpose of limiting the capacity of the magazine of such a firearm.

Owing to the increasing scarcity of game, it has become desirable to limit the number of shots which can be fired from repeating and auto-loading guns without the necessity for hand reloading. A single hunter equipped with a large capacity magazine auto-loading gun can work great destruction, particularly with such game as flying birds; and the present depletion of the stock 15 of game birds and other animals is frequently attributed to the over-effectiveness of modern repeating and auto-loading guns. For the sake of preserving the game, and perpetuating the sport of hunting, it is becoming increasingly common among sportsmen to carry not more than two fresh shells or cartridges 20 in a gun at a time. Many States have laws definitely limiting the capacity of sporting gun magazines to two cartridges. However, 25 there is always in the field the class of shooter who is desirous of equipping himself with the maximum number of cartridges for repeated firing without reloading, and to this end even the normal magazine capacity of 30 guns as distributed by their manufacturers is sometimes increased by the use of magazine attachments and extensions.

One such magazine extension, applied to a well-known type of auto-loading shot gun, is 35 illustrated in the patent to Parsons, No. 1,702,221, February 12, 1929. In this firearm, the magazine tube extends entirely through the fore-end and is closed by a cap screw threaded on to the extending end of the tube 40 and bearing against the fore-end; thus, it becomes a comparatively simple matter to remove the cap screw, withdraw the magazine spring and the follower, and replace the cap screw with a coupling joined to one or more sections of tubing in which the magazine spring and cartridge follower are inserted, thus, greatly increasing the magazine capacity.

It is an object of the present invention to 50 provide a means for preventing the use of

magazine extensions, particularly in guns embodying tubular magazines extending beneath the barrel.

For the purpose of illustration, this invention has been shown as applied to a gun of the type illustrated in the said Parsons patent or in the patent to Browning, No. 659,507, October 9, 1900.

In the drawings:

Fig. 1 is a fragmentary longitudinal side elevation, partly in section, illustrating one form of the invention.

Fig. 2 is an illustration of a development of the end of a magazine tube having the present invention applied thereto.

Fig. 3 is a development of a section of the magazine tube showing a slightly different embodiment of the invention.

Fig. 4 is a side elevation of a magazine tube the capacity of which has been limited to two cartridges by the use of the invention.

Fig. 5 is an elevation of a magazine follower adapted for use with the form of the invention shown in Figs. 1 and 2.

Fig. 6 is an elevation of a magazine follower adapted for use with the form of magazine tube shown in Fig. 3.

The firearm embodies a barrel 10, a receiver 11, and a fore-end 12 which houses a magazine tube 13. Said magazine tube is rigidly secured in the receiver 11, extends throughout the fore-end 12 and has a threaded forward end 14 adapted to receive a cap screw 15, a flange 16 of which abuts the forward face of the fore-end. The gun is of the auto-loading type, a recoil spring 17 surrounding the magazine tube 13 is compressed between the forward end of the receiver and a suitable friction device, indicated generally by numeral 18, which engages the apertured lug 19 rigidly secured to the barrel. Upon firing the gun, the barrel 10 recoils with respect to the receiver, the magazine tube and fore-end; comprising the spring 17 which, at the end of the recoil movement, returns the barrel to the position illustrated. The spring necessarily having considerable power, the barrel lug 19 is brought against the shoulder 20 of the fore-end with very substantial force and the shock of stopping the barrel is trans-

mitted through the material of the fore-end, the engaging threads of cap screw 15 and the magazine tube, and through the magazine tube to the receiver. It is thus essential that every part of the wall of the magazine tube including the threads 14 be of substantial tensile strength in order to sustain the shock load which is applied to them in every operation of the gun.

10 It has been found that a very effective means of preventing the attachment of such magazine tube extensions as shown in the Parsons patent, or of limiting the capacity of the magazine to any desired number of cartridges, comprises forming in the metal of the magazine tube at any desired point a series of indentations, such as 21 and 22 (Fig. 2). In making such indentations the metal is displaced to such an extent that its outer-
15 surface lies within the inner-surface of the cylindrical tube, and the indentations form an abutment which the cartridges in the mag-
azine cannot pass; thus, obstructing the foremost cartridge in a definite position and plac-
20 ing a definite limit upon the capacity of the magazine. Such indentations may be placed at or near the end of the tube, where they cross the threads 14, or they may be placed in any desired location throughout the length
25 of the tube. They may, moreover, extend either longitudinally or circumferentially of the tube, as desired; circumferential indentations being shown at 23 in Fig. 3. Where the indentations are associated with the threaded
30 end of the tube, all or part only of them may terminate at the end of the tube, as shown in Fig. 2. It is quite impracticable to re-
move such indentations, once they have been
35 made, and thereby adapt the gun for a mag-
azine extension or increase the magazine ca-
pacity, for the reason that once the tube wall has been indented in the manner described an attempt to remove the indentations by grind-
40 ing or filing, or to restore this metal to its
45 original position in the cylinder wall, will
inevitably weaken the tube to such an extent that it is incapable to withstand the shock loads to which it is subjected, as hereinbefore described. This is particularly true when the
50 indentations are associated with the threads 14. When the metal of the indentation is removed the thread ceases to be continuous and the application of the heavy shock load as the barrel comes to rest will inevitably
55 rupture the tube metal.

Convenience of assembly requires that the cartridge follower 24 and magazine spring 25 be inserted through the forward end of the tube. Accordingly, the cartridge follower
60 may be given the contour illustrated in Fig. 5 if the tube is indented as shown in Figs. 1 and 2, or the contour illustrated in Fig. 6 if the tube is indented as shown in Fig. 3. The contours illustrated enable the magazine fol-
65 lower to pass the indentations in assembly.

Once the arm is assembled the possibility of the cartridge follower rotating to such a position that its peripheral notches will be in alignment with the tube indentations, per-
mitting the follower to move forward past
70 the indentations, is remote; but, even if the follower should pass the indentations, the first cartridge will be stopped by them. A very efficient means of limiting magazine ca-
pacities and preventing the use of magazine
75 extensions is thus secured.

It is to be understood that the embodiment of the invention shown in the drawings and herein described is merely illustrative, and that the invention may take many other forms, all falling within the scope of the ap-
80 pended claims.

What is claimed is:

1. In a firearm magazine, means for limit-
ing the capacity of the magazine comprising
obstructions projecting inwardly from the
magazine wall, and so related to the magazine
wall that their removal destroys the maga-
zine. 85
2. In a tubular firearm magazine adapted
to contain a column of cartridges, means for
limiting the capacity of the magazine com-
prising indentations in the wall of the maga-
zine tube so designed that their removal sub-
stantially weakens the tube wall. 90
3. In a tubular firearm magazine tube
adapted to contain a column of cartridges,
means for limiting the capacity of said maga-
zine tube comprising tube diameter reducing
devices projecting radially from the tube
wall, and a cartridge follower in said tube
having peripheral recesses adapted to receive
said radial projections. 100
4. A magazine tube for firearms having a
threaded end adapted to receive a cap screw,
and diameter reducing indentations intersect-
ing said thread and so designed that their re-
moval substantially weakens said thread. 105
